UNITED STATES PATENT OFFICE.

EDWARD W. EISENHAUER, JR., OF LOS ANGELES, LOUIS F. FLORMANN, OF SILVER LAKE, AND EMIL C. A. WOLTMANN, OF LOS ANGELES, CALIFORNIA.

WOOD-ASH FURNACE AND EXTRACT-BOILER.

1,341,889.

Specification of Letters Patent.

Patented June 1, 1920.

Application filed January 28, 1919. Serial No. 273,624.

To all whom it may concern:

Be it known that we, EDWARD W. EISENHAUER, Jr., LOUIS F. FLORMANN, and EMIL C. A. WOLTMANN, citizens of the United

5 States, the said EISENHAUER, Jr., and WOLTMANN residents of Los Angeles, Los Angeles county, State of California, and said FLORMANN resident of Silver Lake, San Bernardino county, State of California,

10 have invented certain new and useful Improvements in Wood-Ash Furnaces and Extract-Boilers, of which the following is a specification.

Our invention relates to the class of furnaces especially adapted for the combustion of wood, to produce the ash; and in connection with said furnace, and as a unitary part thereof, a digester for the leaves in which an extract is made, from which a valuable product may be had.

The particular object we have in view is the production of wood-ash both for direct use as a fertilizer, and for the recovery of its potash and other content. A further object is the production of tannic acid.

It has been known for some time that grease-wood, a prickly shrub found extensively on the alkaline plains of this country is rich in potash (K_2O) and we have 30 found further that its leaves are available for the production of tannin.

On account of the nature of grease-wood, probably because of its oily content, it burns with a fierce heat; and it is somewhat difficult to so control its combustion as to avoid appreciable loss by volatilization.

The object of our invention is to provide a furnace in which combustion, while constant and perfect, is under such control that 40 little or no loss occurs by volatilization and all the ash is recovered free from coals, and a further object is to unite with the furnace, a boiler or digester deriving the heat therefrom, and in which the leaves of the 45 grease wood may be treated to produce an extract from which tannic acid may be recovered.

To these ends our invention consists in the novel furnace and in the combination therewith of the extract-boiler, all of which we

shall herein fully describe by reference to the accompanying drawings in which,

Figure 1 is a vertical section of our furnace and boiler, on the line 1—1 of Fig. 2.

Fig. 2 is a horizontal section on the line 55 2—2 of Fig. 1.

Fig. 3 is a sectional view showing a modification in the means for obtaining the ash free from coals.

The furnace comprises a shell 1 of any 60 suitable construction, having a combustion chamber 2 and an ash pit 3. In the shell is fitted freely the grate 4 which is supported at its sides on lugs 5. At its inner end it is supported by an arm or bar 6 which 65 lies freely upon a shoulder at 7. At its outer end a bar 8 secured to or formed with the grate protrudes through the wall of the shell in a vertical slot 9 therein; and under said protruding bar works a continuously 70 revolving cam 10, on a shaft 11 driven by a pulley 12.

The effect of the cam playing under the bar 8 is to lift the grate on the shoulder 7 as a fulcrum, and to drop it again, thereby 75 imparting to it a vertical jarring motion, the tendency of which is to continuously sift the ash and keep the grate clear.

In the ash pit 3 is located an inclined screen 13 to which the upper walls of the 80 pit converge, so that all material passing through the grate-plate falls upon the screen. The foot of the screen 13 projects to the exterior of the ash pit, and said pit is provided with a door 14 to remove the 85 ashes.

Upon top of the furnace shell is fitted a hood 15 having an exit flue 16 for the gaseous products of combustion.

17 is a feed elevator which delivers the 90 material into the upper portion of the shell.

18 is a boiler or digester vessel having a drain 19.

The digesting liquid, such as water, circulates through a lower pipe 20, a pipe 21, 95 in practice a coil, located in a suitable position within the combustion chamber 2 of the furnace shell 1, and an upper pipe 22. Thus the heat of the furnace is utilized to heat the boiler water.

Within the boiler 18 is suspended, by the lines 23, the strainer vessel 24. The screen bottom 24' of the vessel is hinged at one side at 25 and is provided with a trip 5 26 at the other side.

Any suitable means may be employed to drive the cam-shaft pulley 12 and the elevator 17.

The operation of the device is as follows:

10 The grease-wood, previously harvested and cut to suitable proportions is fed to the elevator 17 and by it is delivered to the furnace. The feed is practically continuous, fresh material on top continually serving to 15 check undue upward draft, tending to ash loss. Moreover, by thus keeping down the temperature within safe limits, there is no tendency for the potash to volatilize and pass off. Combustion proceeds perfectly 20 however, owing to the highly inflammable nature of the wood, and as it proceeds, the continuously jarred grate-plate, sifts the ashes through. Some particles, still unconsumed, will, as live coals, also sift through, 25 but as all these together with the ash fall upon the screen 13 in the ash pit, these coals failing to pass through the screen, are separated from the ash which passes through into the pit. The coals are delivered exteriorly by the screen 13 and may be run over again through the furnace. The ashes in 30 the pit may be removed and marketed and used as such for fertilizer, or from them the potash may be recovered and sold, according to the customs or exigencies of business.

Certain substances of value, such for example as iodin, which may volatilize and tend to pass off with the uncondensable or 40 fixed gaseous products of combustion, will be condensed upon the hood 15 from which they may be recovered.

The leaves of the grease-wood, we supply in batches to the strainer vessel 24. When 45 sufficiently digested in the hot water which derives it heat from its circulation through the pipe 21 in the furnace, the strainer vessel is hoisted from the boiler and the bottom 24' of the vessel being tripped, the contents are discharged and a fresh batch of 50 leaves supplied, the hinged bottom being first restored to position. Then the strainer vessel is returned to the boiler. The extract is drawn off through the drain 19 and the tannic acid recovered.

55 In the furnace operation of producing the ash from the wood, it will be seen that the function of the screen 13 in the ash pit is to obtain a pure ash. This result may be reached by other means; and, for an example of such variation, we show in Fig. 3 a 60 modification, in which the screen 13 is omitted, but a blower 27 is applied to one side of the ash pit. The blower is best set at a slight angle in order to direct its air cur-

rent downwardly, and thereby avoid an up-draft, while serving to act chiefly upon the falling material. This air blast tends to fully consume the falling coals, and to blow all the residue thus fully reduced to ash out through a neck 28 into a bin 29 provided 65 with air exit screens 30 and an agitator 31, which latter may be used to prevent the ashes from clogging in the bin, and to facilitate their discharge through the gate 32 of the bin, at such intervals as may be 70 necessary.

We propose in practice to make our device readily portable so that it may be installed in fresh localities according to the abundance of the grease-wood.

We claim:

1. A furnace for the described purpose comprising a shell having a combustion chamber and an ash pit; a grate in the shell dividing said chamber from the pit; means for continuously agitating said grate comprising a rotatable cam co-operating with a part on said grate to raise and lower the same; and means affecting the material falling through the grate to obtain the ash free 85 from coals.

2. A furnace for the described purpose comprising a shell having a combustion chamber and an ash pit; a grate in the shell dividing said chamber from the pit; an elevator for feeding the material to the combustion chamber; means for continuously agitating the grate comprising an operating member co-operating with said grate for moving the same; and means affecting the material falling through the grate to obtain the ash 95 free from coals.

3. A furnace for the described purpose comprising a shell, having a combustion chamber and an ash pit; a tiltable grate 105 freely fitted in the shell between the chamber and pit; a continuously rotating cam acting on one side of said grate to raise and drop it whereby it is continuously jarred; and means affecting the material falling through the grate to obtain the ash 110 free from coals.

4. A furnace for the described purpose comprising a shell, having a combustion chamber and an ash pit; a tiltable grate 115 freely fitted in the shell between the chamber and pit; a continuously rotating cam acting on one side of said grate to raise and drop it whereby it is continuously jarred; and means affecting the material falling through the grate to obtain the ash 120 free from coals consisting of a screen in the ash pit leading to the exterior.

5. A furnace for the described purpose comprising a shell, having a combustion 125 chamber and an ash pit; a tiltable grate freely fitted in the shell between the chamber and pit; a continuously rotating cam

acting on one side of said grate to raise and drop it whereby it is continuously jarred; means affecting the material falling through the grate to obtain the ash free from coals, 5 consisting of a screen in the ash pit leading to the exterior; and an elevator for feeding the material to the combustion chamber.

In testimony whereof we have signed our

names to this specification in the presence of two subscribing witnesses.
